[57] CLAIM

The ornamental design for a auxiliary warning light for automobiles, as shown and described.

DESCRIPTION

FIG. 1 is a front elevational view of the auxiliary warning light for automobiles showing my new design with the wires shown broken away to indicate indeterminate length, and with the broken lines shown for illustrative purposes only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

FIG. 1
